UNITED STATES PATENT OFFICE.

CHARLES F. SHUMAKER, OF SILVER CREEK, NEW YORK.

JARRING MACHINE.

Application filed September 23, 1920. Serial No. 412,250.

To all whom it may concern:

Be it known that I, CHARLES F. SHUMAKER, a citizen of the United States, residing at Silver Creek, in the county of 5 Chautauqua and State of New York, have invented a new and useful Improvement in Jarring Machines, of which the following is a specification.

This invention relates to machines for 10 shaking or jarring containers or other articles.

The objects of the invention are to provide an efficient and inexpensive machine for shaking or jarring articles; also to provide 15 a machine of this kind which automatically takes the articles to be shaken from a supply or stack of articles and shakes the same, and then discharges them from the machine; also to provide a machine of this kind which 20 subjects the articles to a combined rolling and shaking action; and also to improve the construction of apparatus of this kind in the other respects hereinafter specified.

In the accompanying drawings:

25 Fig. 1 is a side elevation, partly in section, of a shaking machine embodying the invention.

Fig. 2 is a fragmentary top plan view thereof on an enlarged scale.

30 Fig. 3 is a transverse sectional view thereof on line 3—3, Fig. 2.

When fruits or vegetables, such as corn have been canned and stored for a period of 35 time, it is found that the water and the natural milk of the corn sometimes separate in the cans, thus spoiling the appearance of the contents of the cans. When these cans are shaken or jarred, the water and milk of the corn again mix and do not again 40 separate upon standing. The machine shown in the drawings will be hereinafter described as used particularly in connection with shaking cans of corn, but it will be understood that it is not intended to limit the 45 invention to such use, since the machine can be used for shaking or jarring other articles.

The machine shown in the accompanying drawings includes a trough or guide portion 50 A for the articles which may be of any desired construction. The trough shown includes a base or bottom member *a* and two side members *a'* which are spaced apart so as to form between them a trough through 55 which the articles may pass. The trough is

provided with a plurality of step members B, those shown being arranged adjacent to the side members *a'* so as to engage the end portions of the articles or cans C passing through the trough. These step members B 60 as shown, each include an elongated, inclined portion *b* over which the cans are adapted to roll and an edge portion *b'* from which the cans are adapted to drop. The step members are preferably also provided 65 with short, inclined portions *b*², the object of which will be hereinafter explained. These step members are preferably arranged upon suitable rails or tracks D which are spaced apart and secured on the base member 70 *a* of the trough, and which in the construction are provided with metallic strips *d* upon which the cans drop. In the operation of the machine the cans roll over the inclined faces *b* and drop over the edges *b'* of the step 75 members onto the track D.

The feeding of the cans through the trough may be effected in any desired manner, this being accomplished in the construction shown by means of a conveyer chain or 80 the like E passing over sprocket wheels *e* *e'* arranged adjacent to the opposite ends of the apparatus. The chain passes lengthwise through the trough, preferably between the rails or tracks D. In order to impart motion 85 to the chain, either of the sprocket wheels may be rotated in any desired manner, a crank *e*² being secured to the sprocket wheel *e'* in the construction illustrated. The conveyer chain is provided with a plurality of 90 flights or fingers F suitably mounted on links of the chain and projecting beyond the same in such a manner as to engage the cans and feed them, preferably one at a time, through the trough A. Any desired means 95 for mounting the flights or fingers on the chain may be employed.

In order to hold the conveyor flights or fingers in proper relation to the trough while passing through the same, the conveyor chain 100 is provided at opposite sides of each finger or flight with a pair of guide members or plates G G'. In the construction shown these guide plates G G' are secured on links arranged respectively in advance and in rear 105 of the link on which the adjacent finger or flight is secured, and the guide plates are provided with side portions or projections which extend into slots, grooves or recessed portions *g*, Fig. 3, of the rails or tracks D, 110

the recessed portions shown being formed by rabbeded portions of the rails D, over which the edges of the metal strips d extend. Hence the extensions of the guide plates G G' rest upon the rail or track D and are held in the recessed portions g by means of the metallic strips or bands d in such a manner as to hold the conveyor flights in substantially upright positions while passing through the trough. Any other means for holding the fingers or flights of the conveyor chain in proper relation in the trough may be provided.

Means are preferably provided whereby the machine will automatically take the cans one at a time from a feed chute or other source of supply. In the construction shown for this purpose, the cans are fed to the machine by means of an inclined chute or track H, having a slotted or bifurcated end portion h through which the flights of the conveyor are adapted to pass, and which terminates at the receiving end of the conveyor trough. This end of the chute H is provided with a pair of stop members h' with which the ends of the cans are adapted to engage and which hold the cans against further movement. Each finger or flight F of the conveyor in passing through the bifurcated end of the chute H engages the foremost can, namely the can resting against the stops h' and elevates the same over the stops and carries it through the trough A. After the foremost can has been removed from the chute H, the other cans roll along the chute until the next can engages the stops. The stops h' are so positioned with reference to the conveyor chain that the flights or fingers F engage only the can which is in engagement with the stops so that each flight or finger carries only one can through the machine at a time. By means of this construction, a number of cans may be placed on the chute H and the conveyor will remove the cans one at a time from the chute and carry them through the trough of the machine. At the discharge end of the machine, rearwardly and downwardly inclined rails or tracks I are provided from which the cans are discharged by gravity from the machine. If desired, the trough A may be arranged at an angle so that the cans pass through the same by gravity, thus eliminating the necessity of using a conveyor.

In the operation of the machine the cans are carried by the flights or fingers of the conveyor over the step members B thereof, passing first upon the upwardly inclined portions b which causes the cans to roll, thus effecting a mixing of the contents thereof. When the cans pass upon the short, downwardly inclined portions b² of the step members they will roll in advance of the fingers and thus drop onto the tracks D

while out of contact with the conveyor flights so that the fingers of the conveyor do not in any way interfere with the free falling of the cans. The apparatus, therefore, subjects the cans to a combined rolling and jarring action, thus ensuring a thorough mixing of the contents of the cans. The apparatus also has the advantage that it requires no attention, the feeding of the cans to the apparatus and the discharge of the cans from the apparatus being accomplished automatically.

I claim as my invention:

1. In a machine for jarring articles, the combination of a pair of guide tracks, a conveyor having upright fingers arranged at intervals thereon, parts on said conveyor which cooperate with said track for holding said fingers in operative positions, and inclined parts on said machine over which said articles are rolled by said fingers and having ends from which said articles drop vertically, each of said fingers carrying only one article at a time through said machine. 80

2. In a machine for jarring articles, the combination of a conveyor chain, consisting of a plurality of links, fingers arranged at intervals on said conveyor, each of said fingers being secured to a link, guide tracks for said conveyor, parts secured to links adjacent to said fingers and adapted to engage with said track for holding said fingers in operative positions relatively to said track, and parts on said track over which the articles are passed by said fingers and from which the articles drop. 90

3. In a machine for jarring articles, the combination of a conveyor chain, consisting of a plurality of links, fingers arranged at intervals on said conveyor, each of said fingers being secured to a link, guide tracks for said conveyor, parts on said conveyor adapted to cooperate with said guide track, said parts being arranged on the links connected with the links to which said fingers are secured and arranged in advance and in rear of said fingers, and inclined members over which said articles are rolled by said fingers and from which said articles drop. 105

4. In a machine for jarring articles, the combination of a trough provided with means for shaking and rolling said articles, a conveyor for passing the articles to said trough, an inclined feed chute for conducting a series of articles to said machine, a rigid stop with which the foremost of said articles engages to limit the movement of said series of articles toward the machine, and fingers on said conveyor adapted to engage the foremost of said series of articles on said chute and carry it over said stop and through said machine, each finger carrying only one article at a time through said trough. 115

5. The combination of a trough, a con- 120

veyor passing through said trough, fingers on said conveyor, a guide track for said conveyor, projections on said conveyor adapted to engage with said guide track to hold said 5 fingers in operative positions, said guide track including metal strips on which articles passing through said conveyor are adapted to roll, and inclined portions in said trough upon which said articles are rolled by said fingers and from which the articles 10 drop to said metal strips.

Witness my hand this 21st day of September.

CHARLES F. SHUMAKER.
